UNITED STATES PATENT OFFICE.

WILLIAM C. BIRMELEY, OF PATON, IOWA.

SELF-LIGHTER FOR CIGARS.

1,153,419.

Specification of Letters Patent. Patented Sept. 14, 1915.

Application filed March 31, 1915. Serial No. 18,401.

To all whom it may concern:

Be it known that I, WILLIAM C. BIRMELEY, a citizen of the United States, and resident of Paton, in the county of Greene and State of Iowa, have invented a certain new and useful Self-Lighter for Cigars, of which the following is a specification.

The object of my invention is to provide a cigar lighter of simple, durable and inexpensive construction.

A further object is to provide such a cigar lighter adapted to be placed on the end of the cigar, and so arranged that the removal of a portion of the lighter ignites inflammable material, sufficiently to light the end of the cigar.

My invention consists in the construction, arrangement, and combination of the various parts of the device, whereby the objects contemplated are attained, as herein-after more fully set forth, pointed out in my claims, and illustrated in the accompanying drawings, in which:

Figure 1 shows a side elevation of a cigar equipped with a lighter embodying my invention. Fig. 2 shows a vertical sectional view of the cigar lighter, installed on the cigar. Fig. 3 shows a transverse vertical sectional view taken on the line 3-3 of Fig. 2.

In the accompanying drawings, I have used the reference numeral 10 to indicate a cigar.

My improved cigar lighter comprises a member 11, having the form of a hollow truncated cone, the larger end of which is adapted to be placed on the cigar, as shown in Fig. 2.

Within the small outer end of the member 11 is a proper amount of inflammable material 12, adapted to be ignited by friction, such for instance, as is used for the heads of matches. The material 12 does not entirely fill the opening at the small end of the opening 11.

The member 13 is of the same general form as the member 11, but slightly larger in diameter and greater in length, and is extended over the member 11 as shown in Fig. 2.

On the small end of the member 13 is a supporting member 14. Extending inwardly from the member 14 are two spring members 15, which are inclined inwardly toward the cigar and away from each other.

On the upper and lower surfaces respec-

tively of the members 15 are strips 16 of suitable material, such, for instance, as is used for scratching safety matches, which extend past the material 12, and are designed to be held in frictional engagement with said material by the spring 15, as clearly illustrated in Fig. 2.

In the practical use and operation of my improved cigar lighter, the device is assembled by placing the member 11 inside the member 13 with the springs 15, having the strips thereon, extending inwardly beyond the material 12, as shown in Fig. 2. The whole device is then placed on the end of a cigar. The parts are so proportioned and arranged, that the material is spaced from the end of the cigar a sufficient distance to allow the springs 15 to project inwardly from the material 12, without contacting with the cigar.

The outer surface of the member 11, and the inner surface of the member 13 are smooth, so that when it is desired to light the cigar, the smoker grasps the outer smaller end of the member 13, pulls it quickly away from the cigar, the member 13 slides off the member 11, causing the strip 16 to scratch the material 12 for igniting it. The member 11 is made of paper which will quickly burn and drop off the cigar. The material 12, and the member 11 are burned long enough to light the end of the cigar.

It will be understood that some changes may be made in the construction, and arrangement of the parts of my improved cigar lighter, without departing from its essential features and purposes, and it is my intent to cover by this application any such changes which may be included within the scope of my claims.

I claim as my invention.

1. A cigar lighter comprising an inner member adapted to fit snugly on one end of a cigar, said inner member being open at both ends, and having on its interior at its outer smaller end inflammable material, capable of being ignited by friction, the outer member adapted to fit over the inner member and having a spring member extended into said inner member adjacent to said inflammable material, and means on said spring members for frictionally engaging said inflammable material when the outer member is pulled away from the inner member for igniting said inflammable material.

2. In a cigar lighter, an inner member having substantially the form of a hollow truncated cone, the larger end of which is adapted to fit on the end of the cigar, inwardly, suitable material on said spring members for frictionally engaging and igniting said inflammable material when the outer member is pulled away from the inner member.

5 inflammable material on the interior of the outer smaller end of said inner member, the outer member having the form of a hollow truncated cone of slightly larger diameter and of greater length than said inner member, a pair of spring members secured to the outer end of said outer member extending
